CONTAINER AND ATTACHMENT THEREFOR

Harry E. Schroeder, Cleveland, Ohio, assignor to
 The Buckeye Forging Company, Cleveland,
 Ohio, a corporation of Ohio

Application July 14, 1938, Serial No. 219,223

14 Claims. (Cl. 221—20)

This invention relates to a container, more particularly to the means which provide for filling and closing the container for shipment and emptying it in a ready manner and to a process of mounting or incorporating one element of the filling, closing and emptying means in the container wall. The invention is shown applied to a sheet metal container (for example, a barrel, drum and the like), but it is obvious that the walls of the container other than the one on which the herein disclosed filling, closing and emptying means are mounted, may be formed of any desired material or combination of materials.

The filling, closing and emptying means herein disclosed may be mounted on any wall of the container, but is shown mounted on one head thereof usually termed the top wall.

One object of the invention is to provide an improved container wherein the support for the closure or closing element is rigidly secured to the container wall.

Another object of the invention is to provide for a container an improved combined closure and emptying device having a removable closing element and means which removably lock the closing element in a predetermined position when loosened to permit emptying of the container.

Another object of the invention is to provide for a container a combined filling, closure and emptying means adapted to be removably mounted in the container wall, whereby other means and devices may be mounted therein.

The present invention also comprehends certain improvements in the construction disclosed in my copending application Serial No. 175,264, filed November 18, 1937.

Other objects of the invention will be apparent to those skilled in the art to which my invention relates from the following description taken in connection with the accompanying drawings, wherein—

Fig. 1 is a plan view of that sheet metal wall for a container (end wall or side wall) on which my filling and emptying means is to be mounted, this view illustrating one step of the process of mounting one element thereof.

Fig. 2 is a section on the line 2—2 of Fig. 1.

Fig. 3 is a top plan view and Fig. 4 is a bottom plan view of the member which is mounted in the container wall.

Fig. 5 is an elevation of the closure.

Fig. 6 is a bottom plan view of the closure.

Fig. 7 is a fragmentary section of the parts in assembled relation and embodying my invention and showing a seal cap in position.

Fig. 8 is a plan of the parts shown in Fig. 7, with portions broken away.

Fig. 9 is a view corresponding to Fig. 7, but showing the closing element positioned to permit emptying, being a section on the line 9—9 of Fig. 10.

Fig. 9a is a view similar to Fig. 9, but showing the container and closure in the position in which emptying of the container takes place.

Fig. 10 is a plan view of the parts shown in Fig. 9, partly in section on the line 10—10 of Fig. 9.

Fig. 11 is a view similar to Fig. 10, but showing a modified form of construction.

Fig. 12 is a fragmentary section on the line 12—12 of Fig. 11.

Fig. 13 is a detail perspective view.

Fig. 14 is a view similar to Fig. 10, but showing another modified form of construction, parts being broken away.

Fig. 15 is a view similar to Fig. 10, but showing another modified form of construction, parts being broken away.

Fig. 16 is a section on the line 16—16 of Fig. 15.

Fig. 17 is a view similar to Fig. 10, showing another modified form of construction, parts being broken away.

Fig. 18 is a fragmentary section showing a combined filling, closure and emptying means, removably mounted in a wall of the container.

Fig. 19 is a fragmentary view showing the supply pipe of a pump mounted in the container wall, after the removable filling, closure and emptying means have been removed.

In the drawings (referring particularly to Figs. 1 to 9 inclusive), 1 indicates a sheet metal wall of a container, for example, a steel barrel or drum having a body and end walls, such wall being for illustrative purposes shown as the top wall thereof, on which is mounted a filling and emptying means, indicated as an entirety at 2, embodying my invention. As shown in Figs. 7, 8 and 9, these means consist of two members indicated at 3, 4, the former consisting of an annulus incorporated in and interlocked to the wall 1, by a "pressed on" process, whereby it is permanently held against movement rotatively and axially, relative to the wall. In carrying out this process, the wall 1 is formed with an opening and the metal there-around is drawn laterally to form a collar 5, having at its base and contiguous to the adjacent portions of the wall 1, offset embossments 6, disposed in spaced relation circumferentially of the collar, six such embossments being

shown. Next, I form the annulus 3. The annulus 3 is shaped to form a side wall 1 and an inwardly extending annular base 8 at its lower end and arranged to engage the wall 1 of the container in surrounding engagement with the collar 5 thereof. At uniformly spaced points, complementary to the embossments 6 on the container wall 1, the metal forming the inner marginal edge of the base 8 is struck up to provide upwardly and inwardly inclined off-sets 9 which form recesses on the lower edge of the base 8, and projecting lugs on its upper edge. To assemble the annulus on the wall 1, it is positioned over the collar 5, with the embossments 6 seated in the recesses formed by the off-sets 9 and interlocked between the side walls thereof against turning relative to the wall 1; then, by means of suitable dies or tools, the marginal portion of the collar 5 is forced or bent outwardly and downwardly throughout its circumference into engagement with the base 8, as shown in Figs. 7 and 8, thereby clamping the base 8 between and in rigid relation to the bent over portion of the collar and wall 1, the dies or tools serving to crimp the collar over the lugs formed by the off-sets 9 and around the ends thereof, to effect an interlock between the collar 5 and base 8 on the upper side of the latter, so as to prevent relative rotative movement between the annulus 3 and wall 1, an interlocked relation being provided between the wall 1 and lower side of the base 8 and between the collar 5 (which is an extended portion of the wall 1) and the upper side of the base 8. By preference, the collar 5, when bent or headed over and upon the base 8, extends substantially to the side wall 1 of the annulus 3, so that when the closure 4 is seated therein and tightened in closed position, its inner portion, or a gasket 10 thereon, may engage directly with such beaded portion of the collar 5 to insure liquid tightness. The inner side of the side wall 1 is provided with screw threads 1' which are engaged by the externally threaded wall 4' of the closure 4 to close or open the opening through the annulus 3, as later set forth. That side of the wall 1 adjacent the container chime or side is extended laterally and formed with converging, curvilinear walls terminating in a pouring lip 7a and substantially diametrically opposite the lip 7a the inner side of the wall 1 is formed with a recess 11, which serves as a vent for the container during emptying thereof, as shown by the arrows in Figs. 9 and 9a. It will be noted that the recess 11 extends from the upper edge of the wall 1 downwardly to a point midway between such edge and lower end of the wall, so that when the closure 4 is unscrewed and backed-off from its closed position far enough to position the inner edge of its threaded wall 4' above the lower end of the recess 11, air is free to pass therethrough and into the container. It will be understood that when a part or all of the contents of the container is to be poured therefrom, it is placed on its side (if the annular 3 is mounted in the container head) as shown in Fig. 9a and then the closure 4 is backed-off to permit flow of the contents from the lip 7a and venting through the recess 11.

It will be understood that the closure 4 is removable from the annulus (see dotted lines in Fig. 9) to permit filling of the container, following which the closure is replaced and tightened into closed position. When it is desired to empty the container, it is laid on its side and the closure backed-up. To prevent backing-up of the closure

too far, that is, far enough to become disengaged from the annulus 3 and thus permit the container contents to gush out and be spilled, I provide a stop means which limits the unscrewing of the closure at a predetermined position, namely, at that point away from the metal seat formed by the beaded over portion of the collar 5, where the side wall of the closure passes the lower end of the recess or vent 11 and effects a connection thereof with the space below the closure. The stop means employed includes a resilient element which yieldingly locks the closure in the predetermined position but permits it to be further unscrewed and removed. The locking means comprising a recess or opening formed in the wall of the closure 4 to provide an abutment and a resilient element carried by or mounted on the annulus 3. For example, the side wall of the closure 4 is formed with a recess to provide a shoulder 12 (see Figs. 5 and 6) extending up from the lower edge of the threads 4' and a section of resilient wire 13 having its opposite ends anchored in openings 14 formed in the side walls 1b of the lip 7a and coiled intermediate its ends to form a laterally extending dog 13a arranged to yieldingly engage and ride the threads 4' of the closure and to drop into the recess and engage the shoulder 12 when the closure is backed-up. As shown in Fig. 6, the dog 13a is disposed in a plane above the shoulder 12 when the closure is in closed position and yieldingly engages the threads 4' so as to engage the shoulder when backing-up of the closure takes place, as shown in Figs. 9, 9a and 10, and may be sprung outwardly to disengage the shoulder 12 when the closure is to be removed.

Figs. 11, 12 and 13 illustrate a modified form of resilient element, consisting of a clip 15 stamped from resilient sheet metal, one end having a foot 15a which is suitably riveted to the inner side of one side wall 1b and its opposite end being arranged to engage the shoulder 12 (see Figs. 11 and 12). In this form of construction I provide the clip with an arm 16 forming a finger hold, which permits the clip to be sprung outwardly out of engagement with the shoulder 12.

Fig. 14 shows another form of resilient element, consisting of a section of resilient wire 17 shaped to substantially fit within the walls of lip 7a and having an extended arm 17a the free end of which is arranged to engage the shoulder 12. That end of the wire 17 remote from the arm is anchored in an opening 17b formed in the adjacent side wall 1b and an intermediate portion of the wire 17 is bent laterally, as shown at 17c and anchored in a recess 17b' formed in adjacent portion of the lip 7a.

Figs. 15 and 16 illustrate another modified form of resilient element, consisting of a section of resilient wire 18 mounted in a recess 18a mounted on the inner side of the side wall 1 of the annulus 3 below its upper edge or rim. One end of the wire 18 is anchored in a laterally disposed opening formed in the side wall 1 and its opposite end portion extends into the lip 7a, its free end being bent inwardly so as to engage the shoulder 12, as shown.

Fig. 17 illustrates another form of resilient element, consisting of a section of resilient wire 19 shaped to surround a portion of the annulus 3, below the rim thereof, one end of the wire being anchored in an opening formed in side wall 1 and its opposite end being bent at right angles inwardly, as shown at 19a and such end

slidably fitting an opening 19b formed in the side wall and extending therethrough so that its free end may engage the shoulder 12, as shown. The side wall 1 is preferably formed with a recess 1x to accommodate the wire 19.

20 indicates a seal cap having a skirt 21 adapted to be crimped inwardly under the shoulder formed by the rim provided on the annulus 3. The seal cap 20 is formed of thin metal capable of ready distortion and serves to detect unauthorized access to the closure 4.

22 indicates as an entirety an adapter which may be applied to the bung ring 1' of a container. In practice the bung ring 1' lends itself as a support for the riser 23 of a suitable pump as shown in Fig. 19, whereby the container may be emptied of its contents, but where it is desired to pour the contents from the container, the riser 23 is removed and the adapter 22 is then mounted in the ring 1', following which the container is laid on its side and the closure thereof backed-up. The adapter 22 consists of an annulus 3x constructed similarly to the annulus 3 to removably receive a closure 4x, but in which the base 8x thereof is provided with an integral collar 24 on that side of the base 8x remote from the side wall 1x of the annulus, the collar 24 being threaded externally and arranged to be threaded into the ring 1'. The adapter 22 being removable, the container may be provided with any form of bung ring and closed and sealed in any suitable manner for shipment and the adapter applied by the user when the container is to be emptied; or if desired, the adapter may be used by the shipper to close the container for shipment.

It will be noted that in the form of construction herein disclosed only one opening is required in and through the container wall to permit filling and emptying thereof, since in the latter operation venting is provided for. By reason of this arrangement only one ring and one closure is needed for each container, so that the cost of manufacturing each container is materially reduced.

It is also to be noted that this application embodies certain improvements in the construction of the annulus and its mounting as compared to the disclosure in my aforesaid application and that no claim is made herein to the subject matter therein disclosed.

To those skilled in the art to which my invention relates many changes in construction and widely differing embodiments and applications of the invention will suggest themselves without departing from the spirit and scope of the invention. My disclosures and the description herein are purely illustrative and are not intended to be in any sense limiting.

What I claim is:

1. A container having a sheet metal wall formed with an opening and provided with a collar surrounding said opening, said collar contiguous to said wall being provided with spaced off-sets, in combination with an annulus provided with a threaded side wall and an inwardly extending base at one end surrounding said collar, the metal of the base being up-set to form recesses on its bottom or outer face complementary to said off-sets and projecting lugs on its top or inner face, said off-sets fitting into said recesses to interlock said collar to the bottom or outer face of said base and the marginal portion of said collar being bent laterally circumferentially to

over said lugs into engagement with the top or inner face of said base, whereby said collar is interlocked thereto.

2. A container having a sheet metal wall formed with an opening and provided with a collar surrounding said opening, in combination with an annulus provided with an internally threaded side wall and an inwardly extending base at one end surrounding said collar, said side

10 wall at one side of said annulus being extended outwardly to form a pouring lip and at another side thereof being formed on its inner face with a recess extending downwardly from its opposite end to form a vent, the marginal portion of said 15 collar being bent laterally circumferentially into engagement with the upper side of said base, interlocking means between said collar and said base, and a closure removably threaded into said side wall and arranged to engage the bent over portion of said collar to close the opening in said metal wall, said closure when backed-up serving to connect said pouring lip and said recess with said opening.

3. A container having a sheet metal wall formed with an opening and provided with a collar surrounding said opening, in combination with an annulus provided with an internally threaded side wall and an inwardly extending base at one end surrounding said collar,

30 the marginal portion of said collar being bent laterally circumferentially over into engagement with the upper side of said base whereby said collar is secured thereto, a portion of said side wall at one side of said annulus being extended

35 laterally to form a pouring lip and another portion being formed with a vent, a removable closure engaging the threaded side wall and arranged to close the said opening when screwed into engagement with said base, and releasable 40 means between said annulus and said closure for stopping the latter, when backed-off, at a predetermined position to connect said pouring lip and vent with said opening.

4. A container having a sheet metal wall formed with an opening and provided with a collar surrounding said opening, in combination with an annulus provided with an internally threaded side wall and an inwardly extending base at one end surrounding said collar,

45 the marginal portion of said collar being bent laterally circumferentially over into engagement with the upper side of said base whereby said collar is secured thereto, a portion of said side wall at one side of said annulus being extended laterally to

50 form a pouring lip and another portion being formed with a vent, a removable closure engaging the threaded side wall and arranged to close the said opening when screwed into engagement with said base, and releasable means between said

55 annulus and said closure for stopping the latter, when backed-off, at a predetermined position to connect said pouring lip and vent with said opening,

60 said releasable means consisting of a shoulder provided on the side portion of said closure and a resilient member mounted within said pouring lip and arranged to engage said shoulder.

5. A container having a sheet metal wall formed with an opening and provided with a collar surrounding said opening, in combination with an annulus provided with an internally threaded side wall and an inwardly extending base at one end surrounding said collar, the marginal portion of said collar being bent laterally circumferentially over into engagement with the

upper side of said base whereby said collar is secured thereto, a portion of said side wall at one side of said annulus being extended laterally to form a pouring lip and another portion being formed with a vent, a removable closure engaging the threaded side wall and arranged to close the said opening when screwed into engagement with said base, and releasable means between said annulus and said closure for stopping the latter, when backed-off, at a predetermined position to connect said pouring lip and vent with said opening, said releasable means consisting of a shoulder provided on the side portion of said closure and a section of resilient wire anchored at its opposite ends in the walls of said annulus and provided intermediate its ends with a laterally extended portion arranged to engage said shoulder.

6. A container having a sheet metal wall formed with an opening and provided with a collar surrounding said opening, in combination with an annulus provided with an internally threaded side wall and an inwardly extending base at one end surrounding said collar, the marginal portion of said collar being bent laterally circumferentially over into engagement with the upper side of said base whereby said collar is secured thereto, a portion of said side wall at one side of said annulus being extended laterally to form a pouring lip and another portion being formed with a vent, a removable closure engaging the threaded side wall and arranged to close the said opening when screwed into engagement with said base, and releasable means between said annulus and said closure for stopping the latter, when backed-off, at a predetermined position to connect said pouring lip and vent with said opening, said releasable means consisting of a shoulder provided on the side portion of said closure and a section of resilient wire mounted on the inner side of said side wall, one end of said wire being anchored to said wall and its opposite end being arranged to engage said shoulder.

7. A container having a sheet metal wall formed with an opening and provided with a collar surrounding said opening, in combination with an annulus provided with an internally threaded side wall and an inwardly extending base at one end surrounding said collar, the marginal portion of said collar being bent laterally circumferentially over into engagement with the upper side of said base whereby said collar is secured thereto, a portion of said side wall at one side of said annulus being extended laterally to form a pouring lip and another portion being formed with a vent, a removable closure engaging the threaded side wall and arranged to close the said opening when screwed into engagement with said base, and releasable means between said annulus and said closure for stopping the latter, when backed-off, at a predetermined position to connect said pouring lip and vent with said opening, said releasable means consisting of a shoulder provided on the side portion of said closure and a section of resilient wire mounted on the outer side of said side wall, one end of said wire being anchored to said wall and its opposite end being arranged to engage said shoulder.

8. A container having a sheet metal wall formed with an opening and provided with a collar surrounding said opening in combination with an annulus provided with an internally threaded side wall and an inwardly extending base at one end surrounding said collar, the marginal por-

tion of said collar being bent laterally circumferentially over into engagement with the upper side of said base whereby said collar is secured thereto, a portion of said side wall at one side of said annulus being extended laterally to form a pouring lip and another portion being formed with a vent, a removable closure engaging the threaded side wall and arranged to close the said opening when screwed into engagement with said base, and releasable means between said annulus and said closure for stopping the latter, when backed-off, at a predetermined position to connect said pouring lip and vent with said opening, said releasable means consisting of a shoulder provided on the side portion of said closure and a section of resilient wire mounted within said pouring lip and having portions anchored to the walls thereof, one end of said wire being arranged to engage said shoulder.

9. A container having a sheet metal wall formed with an opening in combination with an annulus mounted at its inner end in said sheet metal wall in registry with said opening and provided with an internally threaded side wall and a seat, a portion of said side wall at one side of said annulus being extended laterally to form a pouring lip and another portion being formed with a vent, a removable closure engaging the threaded side wall and arranged to close the said opening when screwed into engagement with said seat, and releasable means between said annulus and said closure for stopping the latter, when backed-off, at a predetermined position to connect said pouring lip and vent with said opening.

10. A container having a sheet metal wall formed with an opening, in combination with an annulus mounted at its inner end in said sheet metal wall in registry with said opening and provided with an internally threaded side wall and a seat, a portion of said side wall at one side of said annulus being extended laterally to form a pouring lip and another portion being formed with a vent, a removable closure engaging the threaded side wall and arranged to close the said opening when screwed into engagement with said seat, and releasable means between said annulus and said closure for stopping the latter, when backed-off, at a predetermined position to connect said pouring lip and vent with said opening.

11. A container having a sheet metal wall formed with an opening, in combination with an annulus mounted at its inner end in said sheet metal wall in registry with said opening and provided with an internally threaded side wall and a seat, a portion of said side wall at one side of said annulus being extended laterally to form a pouring lip and another portion being formed with a vent, a removable closure engaging the threaded side wall and arranged to close the said opening when screwed into engagement with said seat, and releasable means between said annulus and said closure for stopping the latter, when backed-off, at a predetermined position to connect said pouring lip and vent with said opening, said releasable means consisting of a shoulder provided on said closure and a resilient member mounted within said pouring lip and arranged to engage said shoulder.

12. A container having a sheet metal wall formed with an opening, in combination with an annulus mounted at its inner end in said sheet metal wall in registry with said opening and provided with an internally threaded side wall and a seat, a portion of said side wall at one side of said annulus being extended laterally to form a pouring lip and another portion being formed with a vent, a removable closure engaging the threaded side wall and arranged to close the said opening when screwed into engagement with said seat, and releasable means between said annulus and said closure for stopping the latter, when backed-off, at a predetermined position to connect said pouring lip and vent with said opening, said releasable means consisting of a shoulder provided on said closure and a section of resilient wire mounted on one side of said side wall, one end of said wire being anchored to said wall and its opposite end being arranged to engage said shoulder.

13. A container having a sheet metal wall formed with an opening and provided with a collar surrounding said opening, in combination with an annulus provided with an internally threaded side wall and an inwardly extending base at its inner end surrounding said collar, said side wall at one side of said annulus being extended outwardly to form a pouring lip and at

5 another side thereof being formed on its inner face with a recess extending downwardly from its outer end to form a vent, the marginal portion of said collar being bent laterally circumferentially into engagement with the upper side of said base, interlocking means between said collar and said base, and a closure removably threaded into said side wall and arranged to close the opening in said metal wall, said closure when 10 backed-up serving to connect said pouring lip and said recess with said opening.

14. A container having a sheet metal wall formed with an opening and provided with a collar surrounding said opening, in combination with an annulus provided with an internally threaded side wall and an inwardly extending base at one end surrounding said collar, said side wall at one side of said annulus being extended outwardly to form a pouring lip and at 15 another side thereof being formed on its inner face with a recess extending downwardly from its opposite end to form a vent, interlocking means between said collar and said base, and a closure removably threaded into said side wall and arranged to engage the base to close the opening in said metal wall, said closure when 20 backed-up serving to connect said pouring lip and said recess with said opening.

HARRY E. SCHROEDER.
